UNITED STATES PATENT OFFICE.

JOHN DESMOND AND THOMAS J. SWEENEY, OF DETROIT, MICHIGAN, ASSIGNEES TO THE PENBERTHY INJECTOR COMPANY, OF SAME PLACE.

DESIGN FOR AN INJECTOR-CASING.

SPECIFICATION forming part of Design No. 24,275, dated May 7, 1895.

Application filed June 5, 1894. Serial No. 513,588. Term of patent 14 years.

To all whom it may concern:

Be it known that we, JOHN DESMOND and THOMAS J. SWEENEY, citizens of the United States, residing at Detroit, in the county of Wayne and State of Michigan, have invented and produced a new and original Design for Injector-Casings, of which the following is a specification, reference being had therein to the accompanying drawing, forming a part thereof, and showing in elevation an injector-casing embodying our design.

The design consists in the fanciful shape and configuration of the casing and comprises the elongated cylindrical portion A having the short cylindrical nipple B near one end, and the elongated cylindrical nipple G on its opposite side. On the cylinder between the nipple G and the opposite end of the cylinder is the elbow or trunk D having a curved outer end abutting against a short cylinder

C which cylinder is separate from and parallel with the cylinder A. Between the cylinders is the stem E located near the outer end of the cylinder C. On the lower face of the cylinder C is the cylindrical nipple F.

The essential feature of the design is the shape of the casing as above described and shown.

What we claim as our invention is—

The design for an injector-casing consisting of the peculiar exterior shape, substantially as shown and described.

In testimony whereof we affix our signatures in presence of two witnesses.

JOHN DESMOND.
THOMAS J. SWEENEY.
